UNITED STATES PATENT OFFICE.

HENRY T. KRUSE, OF JULES, ILLINOIS.

STRAW-STACKER.

SPECIFICATION forming part of Letters Patent No. 433,175, dated July 29, 1890.

Application filed March 22, 1890. Serial No. 344,951. (No model.)

To all whom it may concern:

Be it known that I, HENRY T. KRUSE, a citizen of the United States, residing at Jules, in the county of Cass and State of Illinois, have 5 invented a new and useful Improvement in Straw-Stackers, of which the following is a specification.

Straw-stackers of the class to which my improvement relates are particularly adapted 10 for use in connection with thrashing-machines; and it consists, generally stated, in an elevator or conveyer mounted usually upon a suitable truck, and having an automatic swinging movement whereby straw 15 discharged upon it from the thrashing-machine may be formed into a stack of desired extent. In the formation of the stack provision is made for raising the discharge end of the swinging conveyer from time to 20 time, in order that it may always be at the proper elevation above the stack as the latter increases in height; and it has, so far as I am aware, been usual hitherto to raise the conveyer by means of a rope or other flexible 25 medium secured at one end to the conveyer and at its other end upon a drum or the like turned to wind up the rope and raise the conveyer by means of a crank operated by hand. Serious objections exist to this manner of 30 raising the conveyer, as it is slow, laborious, and inconvenient, and requires that a man leave other duties at frequent intervals during the operation of the device to actuate the raising mechanism.

The object of my invention is to overcome 35 these and other objections to the construction of the raising mechanism for the conveyer hitherto employed by rendering the raising of the latter automatic in the sense 40 that it shall be effected by the driving-power of the device at the will of the operator; and to the above end my invention consists in raising mechanism for the conveyer so arranged with reference to the driving-power 45 of the machine that it may be readily thrown into and out of engagement with the latter for the purpose of controlling the adjustment of the conveyer; and it consists, further, in the general construction and arrangement of 50 the mechanism I employ for the purpose, as well as in details of its construction and com-

binations of parts, all as hereinafter set forth and claimed.

In the drawings, Figure 1 is a broken view, in sectional elevation, of a straw-stacker embodying my improvements, the section being taken on line 1 1 of Fig. 2, viewed in the direction of the arrows and showing only so much of the device as is necessary for intelligent illustration of my improvements; Fig. 60 2, a sectional plan view taken on the line 2 2 of Fig. 1 and viewed in the direction of the arrows; Fig. 3, a view in elevation of the front end of the device or end opposite that on which the conveyer is mounted; and Fig. 4, a 65 broken sectional view illustrating a detail enlarged.

A represents the oscillating supporting-frame for the conveyer and conveyer mechanism, mounted upon a base-plate or turn-table A'. The turn-table is supported upon a truck which, as well as the mechanism for oscillating the frame A, may be of a common construction, and are therefore not illustrated. The conveyer B is also of common 70 construction, pivoted to the frame A at x, and having at opposite sides the upwardly projecting arms t, upon which guide-pulleys t' are provided.

C is the power-shaft having the drive-pulley C', which in the operation of the device is belted to the thrashing-machine, or directly to the engine by which the latter is operated.

D is a vertical shaft journaled toward the top and bottom of the frame A and extending 85 down through the center of the turn-table, below which it is provided with a miter gear-wheel s' in mesh with a beveled pinion s on the power-shaft. The shaft D is further provided with miter gear-wheels s² and s³, located 90 as shown. The top or platform of the device is afforded by a traveling apron E, stretched over rotary drums r r', and shielded on three sides by wind-boards q. A shaft F, journaled in the frame A and having a miter gear-wheel p in mesh with the wheel s³, extends 95 beyond the side of the frame, where it carries a pulley p', to which are belted a pulley r² on the drum r, and the pulley (not shown) which drives the conveyer.

The mechanism for raising the conveyer comprises a shaft G, journaled in the frame

A, having a miter gear-wheel o in mesh with the wheel s^2 and extending beyond the front side of the frame, where it is provided with a pinion o' , having a wide periphery.

5 H is a longitudinally-reciprocating shaft journaled in the frame, to extend parallel with the shaft G, provided at its outer end with a gear-wheel n , which meshes with the pinion o , and provided adjacent to the gear-wheel n with a pinion n' .

Extending across the frame from front to back and parallel with the shafts G H is a shaft I. Upon one end of the shaft I, adjacent to the front side of the device, is a gear-wheel m , located in the path of the pinion n' , which in the backward reciprocation of the shaft H is caused to engage the gear-wheel m and release it in the forward reciprocation of the shaft. At the end opposite the wheel m the shaft I is provided with a worm m' , which meshes with a gear-wheel l on a horizontal shaft K, which extends across the back end of the frame A and beyond the sides of the latter, where it carries drums K'. Ropes 25 or other flexible media L are secured at one end upon the drums K' and extend around guide-pulleys k toward the top of the frame, and thence around the pulleys t' on the conveyer and back to the frame, where they are secured at their opposite ends to eyes i .

The mechanism for producing reciprocation of the shaft H comprises a lever M, fulcrumed at x' upon the frame A and pivotally secured at the free end of its short arm to a collar i , 35 loose upon the shaft H and held against lateral play thereon by fixed collars i' . The long arm of the lever is connected through a stiff rod h with the arm of a crank-shaft N, journaled upon the frame and provided with 40 a ratchet-wheel g . A lever f , pivoted to the shaft N, carries the ratchet g' , and is held normally at the backward limit of its oscillation by a spring f' . A line O, of rope or cord, is secured to the free end of the lever f and 45 may extend to any location where it may be within easy reach of the operator.

While the straw-stacker is in operation, the shafts G and H are caused to rotate continuously. When it is desired to elevate the conveyer B, the operator may pull upon the line O, giving it, say, two tugs to cause the crank-shaft to describe a half-revolution, and thus cause the lever M to reciprocate the shaft H and draw the rotating pinion n' into mesh 55 with the gear-wheel m to produce rotation of the shaft I. The worm-and-gear connection between the shafts I and K causes the latter to rotate and wind the ropes L upon the drums K', which thus raise the conveyer. When 60 the conveyer has reached the desired elevation, two tugs upon the rope O, to reciprocate the shaft H back to its initial position and disengage the pinion n' from the gear-wheel m , will produce immediate stoppage of the 65 rotation of the shafts I K, and the worm and gear $m' l$ will operate to sustain the conveyer in its adjusted position by preventing the

latter by its weight from rotating the shaft K and drums to unwind the ropes L. It will thus be apparent that the rise and stoppage 70 in its ascent of the conveyer may be produced quickly and with comparatively little effort on the part of the operator and from a location at any desired distance from the device.

While I prefer, on account of its simplicity 75 and economy, to employ the raising mechanism for the conveyer constructed and arranged as described, it is of course susceptible of various modifications as to details, which, however, would cause no departure from the spirit 80 of my invention.

What I claim as new, and desire to secure by Letters Patent, is—

1. A straw-stacker having its conveyer-raising mechanism separably connected with the 85 driving-shaft of the machine to be operated thereby, and lever mechanism for producing and separating the connection, substantially as described.

2. A straw-stacker having the raising mechanism for its conveyer separably connected with the driving-shaft of the machine to be operated thereby, lever mechanism for producing and separating the connection, and means, as the rope O, connected with the lever mechanism, through which to operate it and extending beyond the machine, whereby the raising of the conveyer may be produced at any desired distance away from the machine, substantially as described. 90

3. In a straw-stacker, the combination, with the driving-shaft of the machine and the mechanism for raising the conveyer, of gearing operated by the driving-shaft, gearing connected with and operating the raising mechanism, and lever mechanism for throwing the said 100 gearings at will into and out of engagement with each other, whereby the raising of the conveyer is produced by the driving-power of the machine, substantially as described. 105

4. In a straw-stacker, the combination, with the driving-shaft of the machine and mechanism for raising the conveyer, of gearing operated by the driving-shaft, gearing connected with and operating the raising mechanism, lever mechanism for throwing the said gearings at will into and out of engagement with each other, and means, as the rope O, connected with the lever mechanism and extending beyond the machine, whereby the lever mechanism may be operated at any desired 115 distance away from the machine and the raising of the conveyer is produced by the driving-power of the machine, substantially as described. 120

5. In a straw-stacker, the combination, with the driving-shaft of the machine and mechanism for raising the conveyer, of gearing operated by the driving-shaft, gearing connected with and operating the raising mechanism, a longitudinally-movable shaft provided with 130 gearing in continuous engagement with one of the aforesaid gearings and caused by movement of the shaft to engage and release the

other gearing, and lever mechanism for moving the shaft at will, whereby the raising of the conveyer is produced by the driving-power of the machine, substantially as described.

- 5 6. In a straw-stacker, the combination, with the driving-shaft of the machine and mechanism for raising the conveyer, of gearing operated by the driving-shaft, gearing connected with and operating the raising mechanism, 10 a longitudinally-movable shaft provided with gearing in continuous engagement with one of the aforesaid gearings and caused by movement of the shaft to engage and release the other gearing, and mechanism for moving the 15 shaft at will, comprising a lever M, fulcrumed on the frame of the machine, connected at one end with the movable shaft and provided at its opposite end with means, substantially as described, for operating it at any desired distance away from it, whereby the raising of the 20 conveyer is produced by the driving-power of the machine, substantially as set forth.

7. In a straw-stacker, the combination, with the driving-shaft of the machine and mechan-

ism for raising the conveyer, of gearing operated by the driving-shaft, gearing connected with and operating the raising mechanism, a longitudinally-movable shaft provided with gearing in continuous engagement with one of the aforesaid gearings and caused by movement of the shaft to engage and release the other gearing, and mechanism for moving the shaft at will, comprising a lever M, fulcrumed on the frame of the machine and connected at its short arm with the movable shaft, a 30 crank-shaft N, connected with the long arm of the lever, a ratchet-wheel g on the crank-shaft, a ratchet engaging the ratchet-wheel, an operating-cord or the like connected with the ratchet, and a spring f' for returning the 35 ratchet, the whole being constructed and arranged to operate substantially as and for the purpose set forth.
